Primary Examiner — Natasha Vujcic*Assistant Examiner* — Gilbert B Ford(74) *Attorney, Agent, or Firm* — Flynn Thiel, P.C.(57) **CLAIM**

The ornamental design for an evaluation unit for inhalers, as shown and described.

DESCRIPTION

FIG. 1 is a perspective view of an evaluation unit for inhalers showing our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines in the drawings illustrate portions of the evaluation unit for inhalers and form no part of the claimed design.

1 Claim, 7 Drawing Sheets(56)
